HYDRAULIC MOTOR FOR WAGON-DUMPS.

1,098,498.

Specification of Letters Patent.

Patented June 2, 1914.

Application filed July 3, 1911. Serial No. 636,760.

To all whom it may concern:

Be it known that we, STACY B. HART, WALTER B. WILDE, and WALTER FRANK BROWN, citizens of the United States, residing at Peoria, in the county of Peoria and State of Illinois, have invented certain new and useful Improvements in Hydraulic Motors for Wagon-Dumps, of which the following is a specification.

Our invention relates to certain new and useful improvements in hydraulic motors for wagon dumps.

The object of the invention is to provide hydraulic means for raising the wagon, means for controlling the movement of the piston with relation to a cylinder under all conditions that may arise in the use of the device; to dispose the pump substantially within the cylinder and to generally simplify the structure and minimize the number of parts necessary to the building of the same.

We have shown the device particularly associated with an overhead derrick; it may, however, be associated with other forms of dumps without departing from the principle involved in the structure disclosed.

Our invention consists in the association of the parts in a relation to simplify the structure and to reduce the number of structural parts to the minimum.

Our invention further consists in placing the pump within a liquid containing portion of the device.

Our invention further consists in the association with liquid circulating parts of a three way control valve adapted in function to accommodate varying conditions and circumstances of use of the device for dumping purposes.

Our invention further consists in novel combinations and details of construction hereinafter more particularly set out.

Referring to the drawings,—Figure 1 is a perspective view of a derrick dump showing our invention applied; Fig. 2 is a vertical section of a cylinder and pump, connections between the cylinder and pump, and valves and other means of control; Fig. 3 is a vertical section showing the pump, control valves and certain pipe connections; Fig. 4 is a detail view of a valve, and Fig. 5 is a

sectional view taken on the line 5—5 of Fig. 4.

Other features hereinafter specifically set out are new.

In the drawings, 2 is a cylinder, 3 a head or cap and 4 a gasket interposed therebetween. The head 3 is provided with a duct as 5 communicating with the upper portion 60 of cylinder 2. This head is also provided with air chamber 6.

7 refers generally to a casting designed to contain the pump parts. This casting has an interior opening, the purpose of which is 65 to provide for the proper seating of the pump and also to provide an auxiliary liquid containing chamber within which an eccentric for operating the pump may be placed. The upper portion of the casting is 70 provided with offset or shoulder 8 which forms the seat for partition 9, the latter being provided with opening 10 therein.

11 is a gasket positioned upon the upper wall of partition 9, upon which said gasket 75 the lower end of cylinder 2 is adapted to be seated.

12 is an auxiliary chamber communicating with the interior of cylinder 2 and contains the structural parts of an eccentric and its 80 connections.

13 is a compensating chamber communicating with auxiliary chamber 12 through opening 13a.

14 refers generally to a pump which may 85 be of any suitable type but as we are not claiming in this application any patentable novelty in the pump, detail description of the same is omitted.

15 is a valve normally seated in a suitably 90 formed valve seat in the body of the casting.

16 is a coil spring and 17 is a set nut seated in the threaded opening in the bottom of casting 7 adapted to induce a proper tension of spring 16 upon valve 15.

18 is a three way valve seated in a suitable opening within casting 7 and suitably held therein in a relation to permit the same to be turned by any suitable means, as for instance, lever 19.

20 is a central chamber or valve opening within valve 18 communicating with the pump and with ports *a* and *b* in the valve.

21 is a by-pass in the body of casting 7

95

100

- communicating with auxiliary chamber 12 and adapted for intermittent communication with the valve opening 20 through port *b*.
- 5 22 is a tube communicating at its upper end with duct 5, the same being threaded for connection with a threaded opening entering said duct 5. The lower end of tube 22 communicates through duct 23 and port *a* 10 with valve opening 20 and is threaded at its lower end for connection with an opening communicating with duct 23.
- 24 is a lug on casting 7, its functional adaptability being to assist in the proper 15 joining of the cylinder 2 with head 3 and casting 7. Sleeve nut 26 is supported in a threaded connection in the opening leading to duct 23 and is interiorly threaded, to connect with the lower threaded end of 20 tube 22.
- 25 is a nut carried on the threaded part of the lower end of tube 22. Nuts 25 and 26 serve the purpose of properly drawing the cylinder 2, head 3 and casting 7 together.
- 25 27 is a tube communicating at its upper end with air chamber and at its lower end with compensating chamber 13, its ends being threaded to engage threaded openings in head 3, and casting 7, to facilitate the drawing and the holding of the parts together.
- 28 is a piston rod and 29 a piston head adapted to reciprocate within cylinder 2.
- The cylinder, auxiliary chamber and all intercommunicating connections are adapted 35 to be filled with liquid, preferably oil.
- In the operation of the device, and at the beginning of the raising movement, valve 18 is turned into a position so that the opening 20 therein will communicate with tube 40 22, then the pump being in operation will force the liquid into the cylinder above the piston head, forcing it downwardly, which action, through the connection of extension 30 of the piston rod with ropes 31 of the 45 dump derrick will cause the latter to be drawn downwardly and through the action of the loops thereon engaging the hubs of the wheel, the wagon will be raised. We do not consider it necessary to describe in detail 50 the connection with the derrick, as such structural connections are old and constitute no part of this invention, except in the combination employed. When the piston has reached the limit of its downward movement necessary to raise the wagon to the 55 desired height, the valve 18 may be turned to a position in which port *b* communicates with by-pass 21 and closes port *a*, in which position the piston will be held against upward movement, thus sustaining the wagon in a fixed position. During the time the 60 wagon is held in this fixed position the liquid discharged from the pump will pass through valve opening 20, port *b* and by-pass 21 back 65 into auxiliary chamber 12. When it is de- sired to lower the wagon, valve 18 may be turned so that ports *a* and *b* therein will register throughout a portion of the capacity of said ports with by-pass 21 and duct 23. Under such condition of adjustment of the 70 valve, the weight of the wagon will cause piston head 29 to be drawn upwardly, expelling the liquid from the upper portion of cylinder 2, the escape thereof being effected through the communicating connection back 75 to auxiliary chamber 12, and likewise into the cylinder below the piston head. During this lowering movement, the discharge from the pump will be into valve opening 20 and into by-pass 21 into auxiliary chamber 12, 80 the capacity of by-pass 21 being sufficient to accommodate the dual flow of liquid from the upper portion of the cylinder and the pump.
- The upward or downward movement of 85 the wagon may be stopped at any point by simple manipulation of the valve 18. The speed of ascent or descent may be controlled at the will of the operator by manipulation of this same valve so as to increase or diminish the relative flow through the respective ports *a* and *b*. For instance, if the wagon is moving upwardly too rapidly, a turning of valve 18 to partially close the communicating opening from port *a* into 90 duct 23 and causing a degree of opening and communication between port *b* and by-pass 21 will diminish the quantity of liquid passing through duct 23, and the excess of liquid will pass through by-pass 21 back into the 95 auxiliary chamber. The speed in any direction of movement of the piston head may always be regulated by the manipulation of the valve to proportion the flow through 100 respective ports *a* and *b*.
- Chamber 13 and tube 27 are provided to 105 compensate for the displacement occasioned by piston rod 28 as it is projected into cylinder 2. The complete area of cylinder 2 and its communicating connections being filled 110 with liquid, when the piston head is at its most elevated position it follows that as the piston rod 28 is projected into the cylinder the liquid, in proportion to the displacement, 115 will be forced through opening 13^a into compensating chamber 13 and upward into tube 27, proportionately as the piston rod is projected within the cylinder. Upon a reverse movement of the piston head, the liquid from tube 27 and chamber 13 will flow back 120 into the auxiliary chamber 12.
- A compensating displacement chamber associated with hydraulic jacks is not new in principle and therefore we make no claim broadly therefor and claim in our structure 125 only the new feature of utilizing tube 27 as a portion of the compensating chamber, and also as a means, in conjunction with tube 22 which likewise performs a double function, for holding the parts together.

We have shown herein one form of construction of our device. However, it may be differently constructed and the principle thereof applied in different forms without departing from the spirit of the invention, therefore, we desire to claim all forms and structural combinations falling within the principle of the same.

What we claim is:

1. In combination with a hydraulic cylinder provided with an inlet above the piston head and an outlet below the same, and with a by-pass intermediate the inlet and the outlet communicating with the cylinder below the piston, of a valve having an interior opening communicating with the outlet and with ports disposed relatively to communicating means with the cylinder above the piston and with a by-pass so that the shifting valve may establish communication or shut it off so that when there is a flow in one, the other port is closed, or may be turned to permit a partial flow into each.

2. In combination, a hydraulic cylinder, a piston therein, a pump connected with the lower end of the cylinder, an outlet for the cylinder below the piston head through the pump, an inlet to the cylinder above the piston head, a by-pass between the outlet and inlet into the cylinder communicating with the same below the piston head, a valve communicating with the discharge outlet of the pump and with the cylinder above the piston head and with the by-pass, and provided with ports to completely or partially open and close communication with the cylinder above the pump and with the by-pass or to permit a simultaneous flow through each, means under the control of the operator for turning the valve to accomplish its several purposes.

3. In combination, a hydraulic cylinder, a piston therein, an auxiliary cylinder chamber communicating with the lower portion thereof, both cylinders adapted to contain liquid as oil, a pump within the auxiliary chamber, the working parts immersed in the liquid contained therein, a tube communicating with the cylinder above the piston head, a by-pass between the discharge outlet from the pump and the tube connection with the cylinder above the piston head, a valve provided with an interior opening communicating continuously with the discharge opening from the pump and both alternately and simultaneously according to manipulation, through suitable ports with the tube and the by-pass.

4. In combination, a main cylinder, a piston therein, an auxiliary cylinder communicating with the main cylinder below the piston head and forming substantially a continuation thereof, said auxiliary cylinder having a depending portion adapted to carry pump parts, a pump carried within the aux-

iliary cylinder and the extension therefrom, a discharge outlet from the pump, a tube communicating with the cylinder above the piston head, a by-pass disposed between the inlet of the tube and the discharge opening from the pump, a valve supported in the extension from the auxiliary cylinder in a relation to communicate permanently with the discharge opening from the pump and both intermittently and continuously with the tube and the by-pass, and means for effecting the movement of the valve to accomplish the several functions named.

5. In combination, a main cylinder, a piston therein, an auxiliary cylinder communicating with the main cylinder below the piston head and forming substantially a continuation thereof, said auxiliary cylinder having a depending portion adapted to carry pump parts, a pump carried within the auxiliary cylinder and the extension therefrom, a discharge outlet from the pump, a tube communicating with the cylinder above the piston head, a by-pass disposed between the inlet of the tube and the discharge opening from the pump, a valve formed with an interior opening communicating continuously with the discharge opening from the pump and provided with circumferentially elongated ports arranged in different planes but portions of each port lying in the same plane, said ports adapted to register respectively with a communicating connection with the tube and with the by-pass for the purpose of effecting through manipulation of the valve, a communication or cut-off respectively with each the tube and the by-pass or to permit simultaneously an interflow through each, and means for operating the valve to accomplish the functions specified.

6. In combination, a cylinder, a piston operatively connected therewith, a chambered extension communicating with the lower end of the cylinder and valves within said extension, pump parts comprising a shaft, an eccentric and plunger within said extension; a duct communicating with the cylinder above the piston head, a by-pass interposed between said duct and the discharge opening from the pump and a valve interposed between the duct communicating with the cylinder above the piston and with the discharge outlet from the pump and with the by-pass at a point intermediate the tube and the pump discharge outlet, the communicating openings from the valve relatively to the pump, the by-pass and the duct to be such that there shall be a continuous inflow from the pump to the valve and both an alternate and a simultaneous communication to the duct and the by-pass according to the position of the valve, and means for manipulating the valve to establish such communication respectively with the duct and with the by-pass as specified.

7. In combination, a cylinder, a piston operatively connected therewith, a chambered extension communicating with the lower end of the cylinder and valves within said extension, pump parts comprising a shaft, an eccentric and plunger within said extension; a duct communicating with the cylinder above the piston head, a by-pass interposed between said duct and the discharge opening from the pump, and a valve interposed between the duct communicating with the cylinder above the piston and with the discharge outlet from the pump and with the by-pass at a point intermediate the tube and the pump discharge outlet, formed with an interior opening having a permanent communication with the pump outlet and provided with ports arranged relatively in different planes but portions of each lying within the same plane, said ports adapted to communicate respectively with the tube and the by-pass so that each may be closed or opened alternately or each may be partially opened so as to permit a simultaneous flow through each.

8. In combination, a cylinder, a piston operatively connected therewith, a chambered extension communicating with the lower end of the cylinder and valves within said extension, pump parts comprising a shaft, an eccentric and plunger within said extension; a duct communicating with the cylinder above the piston head, a by-pass interposed between said duct and the discharge opening from the pump and a valve interposed between the pump outlet and the duct provided with a communicating opening therein from the former to the latter and with the by-pass at an intermediate point, the communication from the pump with the valve being continuous and with the duct and by-pass both alternate and simultaneous, whereby the flow may be from the pump to the valve and tube to the cylinder above the piston head while the by-pass is closed or from the pump through the by-pass into the auxiliary cylinder while communication with the tube and the cylinder above the piston head is closed or from the pump through the by-pass and from the tube and cylinder portion above the piston head through the by-pass simultaneously.

9. In combination, a hydraulic cylinder, a piston therein, a pump communicating with the cylinder at one end and communicating from the pump with the other end of said cylinder, a by-pass interposed between the pump and the end of the cylinder at which the raising force is applied and communicating with that portion of the cylinder, and a valve interposed between the pump, the by-pass and the portion of the cylinder where the power is applied to effect the raising movement provided with an interior opening communicating continuously with

the pump and both alternately and simultaneously with the by-pass and the connection with the cylinder to apply the raising force, and means for turning the valve to effect the several functions specified.

10. In combination, a hydraulic cylinder, a piston therein, a pump communicating with the cylinder at one end and communicating from the pump with the other end of said cylinder, a by-pass interposed between the pump and the end of the cylinder at which the raising force is applied and communicating with that portion of the cylinder, and a valve interposed between the pump, the by-pass and the portion of the cylinder where the power is applied to effect the raising movement, formed with an interior opening communicating continuously with the pump and with ports opening out therefrom arranged relatively in different planes but portions of each lying in the same plane adapted respectively to register with the communicating means to the portion of the cylinder where it applies the power to effect the raising and with the by-pass and in a relation that by the manipulation of the valve communication with the cylinder may be established when the by-pass is cut off or communication may be established with the by-pass and communication with the cylinder cut off or an interflow from the cylinder to the by-pass and from the pump to the by-pass may be simultaneously established.

11. In combination with a hydraulic cylinder, of an auxiliary chamber communicating therewith provided with an extension adapted to carry pump parts, a shaft carried through the extension, eccentric parts supported thereon, a pump actuated by the eccentric, means connecting the discharge opening from the pump with the auxiliary chamber and with the upper portion of the cylinder, and means for controlling the interflow of liquid therebetween.

12. In combination with a hydraulic cylinder, of an auxiliary chamber communicating therewith provided with an extension adapted to carry pump parts, a shaft carried through the extension, eccentric parts supported thereon, a pump actuated by the eccentric, a duct adapted for communication between the pump and the portion of the cylinder above the piston head, a by-pass disposed between the outlet from the pump and said duct adapted for communication with the cylinder below the piston head, and a valve adapted to control the interflow between the pump and the cylinder above and below the piston head.

13. In combination with a container adapted to be filled with oil, comprising a cylinder and a communicating chambered extension, of a piston and piston rod within the cylinder, a pump, and means for com-

- munication between the pump parts within the liquid container and immersed in liquid therein, and the cylinder above and below the piston.
- 5 14. In combination, a liquid container comprising a cylinder and a communicating chambered extension, a piston and piston rod, pump parts comprising a drive shaft, eccentric and plunger supported within the 10 chamber immersed in the liquid, and means for communication between the pump and the cylinder above and below the piston.
- 15 15. In combination, a liquid container comprising a cylinder and a communicating chambered extension, a piston in the cylinder, pump parts within the liquid container, a discharge outlet from the pump, means connecting the discharge opening from the pump to the cylinder above and 20 below the piston head, and means for controlling the interflow between the portions of the cylinder above and below the piston head.
- 25 16. In combination, a cylinder, a piston adapted for reciprocation therein, an auxiliary chamber communicating with the cylinder below the piston head provided with an extension adapted to carry pump parts and a valve, a pump within the auxiliary 30 chamber and the extension therefrom, a discharge outlet from the pump, means connecting the discharge outlet to the cylinder above and below the piston head, a valve for controlling the interflow therebetween and a 35 compensating chamber adapted to take up the excess liquid displaced by the projection of the piston rod within the cylinder comprising a tube communicating with the cylinder through the auxiliary chamber.
- 40 17. In combination, a cylinder, a piston and piston rod therein, a liquid container, pump parts comprising a drive shaft, an eccentric and plunger supported and immersed in the liquid within the liquid container, a discharge outlet from the pump, means connecting the discharge outlet with the cylinder above and below the piston, a 45 valve for controlling the interflow therebetween, means for actuating the valve, and a 50 compensating duct communicating with the cylinder below the piston head adapted to take up the excess liquid displaced by the projection of the piston rod within the cylinder.
18. In combination, a cylinder adapted to be filled with liquid, an auxiliary chamber formed with flanged parts adapted to be seated in conjunction with the lower portion of the cylinder and an extension therefrom adapted to carry pump parts and a 55 valve, a by-pass formed in said extension, a pump and discharge opening therefrom, a tube communicating with the duct inlet into the cylinder above the piston and connected with the extension from the auxiliary chamber and adapted for communication with the discharge outlet from the pump, a valve 60 communicating with the discharge outlet from the pump, with the by-pass and with the tube communicating with the cylinder 65 above the piston head, a tube having a threaded connection with the cap and communicating with the air chamber therein, and having a threaded connection with the auxiliary chamber and also a liquid communicating connection therewith.
- 70 19. In combination, a cylinder adapted to be filled with liquid, a closure head therefor, a piston therein adapted to be reciprocated under pump pressure in one direction, an auxiliary chamber, means for connecting the cylinder, the head and the auxiliary chamber comprising tubes and means for establishing communication through said tubes 75 between the portions of the cylinder above and below the piston head, and means for taking up the excess liquid displaced by the projection of the piston rod within the cylinder communicating with the said cylinder below the piston head, the said tubes 80 constituting the same means that are employed to establish communication as set forth.
- 85 In testimony thereof we have affixed our signatures in presence of two witnesses.
